[57] CLAIM

The ornamental design for an adjustable baggage strap, as shown and described.

DESCRIPTION

FIG. 1 is an environmental perspective view of an adjustable baggage strap in a fastened position showing our new design;

FIG. 2 is an unfastened, enlarged bottom plan view thereof;

FIG. 3 is a top view thereof;

FIG. 4 is a left side view thereof;

FIG. 5 is a right side view thereof;

FIG. 6 is a front view thereof; and,

FIG. 7 is a rear view thereof.

The claimed design is shown broken away in FIGS. 2-7 for ease of illustration.

The broken line showing of baggage is for illustrative purposes only and forms no part of the claimed design.

The cross-hatched shading represents a cloth material and is understood to cover the entire surface.
